UNITED STATES PATENT OFFICE.

JOHN LEUENBERGER, OF CAMDEN, OHIO.

WASHER OR GASKET CUTTER.

SPECIFICATION forming part of Letters Patent No. 352,139, dated November 9, 1886.

Application filed July 30, 1886. Serial No. 209,579. (No model.)

To all whom it may concern:

Be it known that I, JOHN LEUENBERGER, a resident of the town of Camden, Preble county, and State of Ohio, have invented certain new and useful Improvements in Washer or Gasket Cutters, of which the following is a specification.

The various features of my invention, and the advantages arising from their use, will be apparent from the following description and claims.

In the accompanying sheet of drawings, forming part of this specification, Figure 1 is a side elevation of a device illustrating my invention, the diameter of axle to which the calipers are set being shown in dotted lines at the foot of said device. Fig. 2 is a view in elevation of the same dimensions as in Fig. 1, the lower part of the shank, sliding bar, calipers, and shank of knives being shown in section, and illustrating the connection of said knives and calipers to said sliding bar.

A represents the shank, the upper end of which is of a suitable shape to engage with an ordinary auger-bit or other implement, and at the lower end of said shank A, and constituting a part of same, is the point or pointer D. The lower end of this shank, just above the pointer D, is made hollow to suit the configuration of the sliding bar B, and in said hollow or space said bar slides when the calipers are being adjusted to the sized axle or other object for which a gasket or washer is desired to be cut. At this point of the shank is preferably attached a thumb set-screw, S, for holding the sliding bar in position after it has been set for any given dimension of washer or gasket to be cut.

On one side of the shank A, preferably about midway its length, is cast or otherwise united to it one part, C, of the calipers. The other part, C', of the calipers is attached to the part C, preferably by a screw-connection, as shown, but may be connected by a rivet or other device that will allow of pivotal play of the part C'. This part C' of the calipers is preferably made in the shape shown in the drawings, the lower end of which is in the form of a graduating-arc. In this arc is cut or forged out a graduating-slot, as C', through which is passed the bolt or screw-stud B', which screw or bolt is fastened in the end of the sliding bar B, preferably as shown. In that end of the slid-

ing bar B which is opposite the end to which the arc of the calipers is attached a slot, B', is present, in which the shank of knife D' is made adjustable to cut different widths of gaskets or washers. The knife D' is preferably rigidly attached to the sliding bar B at the inner end of the slot B'. The knife D' is, after being adjusted to the desired width of washer or gasket to be cut, firmly attached to the bar B in the slot B', preferably, as shown, by means of a thumb-screw, d', screwed on the upper part of the shank d of the knife. By turning this thumb-screw d', the shoulder d³ of the knife D' is brought up tight against the under surface of the sliding bar B, and thus serves to keep this knife in position.

The advantage of this cutter over those now in use is at once apparent. In the cutters heretofore made the dimensions of the object for which a washer or gasket is to be cut must first be taken by a rule or similar device, and then the knives must be set by loosening the thumb-screws and taking the dimensions from the rule, and setting the knives correspondingly with the center-pin, which requires considerable time and delay, and is often unsatisfactory. In my device all that is required in order to cut a washer or gasket of the desired dimension is simply to loosen the thumb-screw S, and place the points of the calipers on opposite sides of the diameter of the object for which a washer or gasket is required, as shown in dotted lines in Fig. 1, and then tighten the thumb-screw S, the construction and position of the calipers and graduating-slot C' in relation to the sliding bar and pointer D being such that, when the dimension of the object for which a washer is to be cut is taken, the distance from knife D' to pointer D represents one-half the diameter of the washer to be cut.

When desired, my device may be advantageously employed in cutting circular disks, and in that case all that is necessary is simply to dispense with the adjustable knife B', the diameter of said disk being determined the same as in cutting washers.

What I claim as new and of my invention, and desire to secure by Letters Patent, is—

1. In a washer or gasket cutter, the combination of main shank A, calipers C C', sliding bar B, and a graduating device or attachment, substantially as and for the purposes specified.

2. In a washer or gasket cutter, the combination of shank A, calipers C C', provided with graduating-slot C², sliding bar B, and screw B², substantially as and for the purposes specified.

3. In a washer or gasket cutter, the combination of shank A, calipers C C', provided with graduating-slot C², screw B², sliding bar B, knife D', screw S, and pointer D, substantially as and for the purposes specified.

4. In a washer or gasket cutter, the combination of shank A, calipers C C', provided with graduating-slot C², screw B², sliding bar B, slot B', knives D' D², screw S, and pointer D, substantially as and for the purposes specified.

JOHN LEUENBERGER.
